(57) **CLAIM**

The ornamental design for a surgical instrument organizer, as shown and described.

DESCRIPTION

FIG. 1 is a front perspective view of a surgical instrument organizer, showing my new design;

FIG. 2 is a front elevation view thereof, where a rear elevation view is a mirror image thereof;

FIG. 3 is a left side elevation view thereof, wherein a right side elevation view is a mirror image thereof;

FIG. 4 is a top plan view thereof; and,

FIG. 5 is a bottom plan view thereof.
